3 Claims. (Cl. 182—152)

This invention relates to scaffolds.

More particularly, this invention relates to a type of scaffold which is generally made up of only one or two mobile units, each unit foldable to a collapsed compact form suitable for ready handling, transportation and storage.

The applicant provides a collapsible scaffold unit wherein all the parts except the platform elements are joined or connected by pivoted connections in such a way that each element remains a part of the scaffold unit whether the unit is in set-up condition or collapsed. The applicant has provided a scaffold unit which can be readily set-up, dismantled, moved, transported and stored by a single person. The applicant has further provided a scaffold unit which can be hingedly connected to a second similar scaffold unit to form a scaffold of double length and, consecutively, one of the scaffold units can be swung, upside-down, above the other scaffold unit providing a scaffold of double height.

A preferred mobile scaffold unit of the invention comprises a scaffold frame section supported by a wheeled carriage. The scaffold frame section comprises two upright end frames with at least one X-brace between the end frames to hold them rigid. The carriage comprises a horizontal base frame having a castor at each corner and a pedestal projecting upward from each end. The pedestals support the scaffold frame section at a level displaced from the horizontal plane of the base frame. In the set-up state, each pedestal directly supports one of the end frames of the scaffold frame section. One of the end frames is pivotally attached to its pedestal. The other end frame is disconnectably attached to its pedestal.

At least one X-brace is disposed between the end frames. The X-brace is composed of two cross bars pivotally attached at their mid points. The lower end of each cross bar is pivotally attached to a lower part of an end frame while the upper end of each cross bar is disconnectably connected to the upper part of an opposite end frame. Preferably there are two X-frames, one at each side of the scaffold unit.

By disconnecting the disconnectably attached parts of the scaffold and moving one end frame against the other end frame and then rotating the folded scaffold frame section against the base frame, the scaffold can be collapsed into a compact readily storable unit.

The scaffold frame section is readily detachable from its carriage, and the ends of the upright end frames are adapted so that the scaffold frame sections can be stacked one on top of another to provide a scaffold of the desired height.

Two mobile scaffold units of the invention can be joined back-to-back by hinge elements attached to the upper ends of the back end frames. Connected together by the hinge elements, one scaffold unit can then be conveniently swung up on top of the other scaffold unit in upside-down position, the front end frames being joined together by cooperating fastening means. The second section can be swung up with or without its carriage. A scaffold of more than two sections can be erected by removing the carriage from the second section before mounting the third section.

2

A detailed description of the specific embodiment of the invention will now be set forth with particular reference to the accompanying drawings in which:

FIGURE 1 is a side-elevation view of the folding scaffold of the invention in set-up condition.

FIGURE 2 is a top plan view of the folding scaffold of the invention in set-up condition, with the platform in phantom line.

FIGURE 3 is a broken front end elevation.

FIGURE 4 is a fragmentary rear end elevation along the line 4—4 of FIGURE 1.

FIGURE 5 is a longitudinal cross-section along the line 5—5 of FIGURE 4, showing the detail of the pivotal attachment between the back end frame and its pedestal.

FIGURE 6 is a transverse cross-section along the line 6—6 of FIGURE 1, showing the detail of the disconnectable connecting means between the front end frame and its pedestal.

FIGURE 7 is a longitudinal cross-section along the line 7—7 of FIGURE 6 showing in detail the disconnectable connecting means shown in FIGURE 6 and in particular the locking means for the disconnectable connecting means.

FIGURE 8 is a transverse cross-section along the line 8—8 of FIGURE 1, showing the disconnectable connecting means between the upper part of one of the cross bars and the upper part of the end frame.

FIGURE 9 is a fragmentary and broken plan view of the top of the back end frame showing the hinge connecting elements in detail.

FIGURE 10 is a plan view of a platform useful in the invention.

FIGURE 11 is a broken longitudinal cross-section of the platform along the line 11—11 of FIGURE 10.

FIGURE 12 is a line drawing showing the scaffold of the invention partly folded.

FIGURE 13 is a side elevation of the scaffold of the invention showing it completely folded.

FIGURE 14 is a line drawing in side elevation showing two units hinged together to form a scaffold of double length or double height.

The specific embodiment of the invention shown in the drawings is made up of a carriage A, a scaffold frame section B, and a platform C.

The carriage A comprises a horizontal base frame having castors at each of its four corners. The horizontal base frame comprises a pair of parallel side members 1, separated by a pair of parallel end members 3. The end member 3 located at the front end of the carriage is spaced from the ends of the side members 1, while the other end member is located at the other end of side member 1. A crossbar 41 is located on the horizontal base frame intermediate the end members 3. This crossbar 41 supports the scaffold frame section in collapsed condition.

The pedestal extends upwards from the horizontal base frame along each of the end members 3, the pedestal at the front end of the carriage comprises two uprights 5. The pedestal along the back end member 3 comprises two uprights 7 headed by a tubular member 9. The width of the front pedestal is the same width as the scaffold frame section, while the back pedestal is somewhat wider than the scaffold frame section.

The front end frame of the scaffold frame section comprises two upright end frame members 11, separated by transverse frame members 13. The lower ends of the upright frame members 11 abut the ends of the uprights 5 of the pedestal and are secured by means of pins 29. The back end frame comprises a pair of parallel upright end frame members 15 separated by more of the transverse frame members 13. The back end frame is pivoted to its pedestal around the tubular head element

9 of the pedestal. The tubular head element 9 is peened at one end and cotter pinned at the other to permit complete separation of the scaffold frame section from the carriage.

The two end frames of the scaffold frame section are connected, and can be held rigid, and upright by an X-brace which comprises two cross bar elements 17 pivotally adjoined at the mid point 19. The leg of each cross brace is pivotally mounted in brackets 21 attached adjacent the lower ends of the end frame members 15 on one side of the scaffold unit. The top ends of each cross brace are disconnectably connectable to brackets 23 attached adjacent the upper ends of the opposite end frame members.

On all the disconnectable connections between parts of the scaffolds of the invention, the parts are locked together by means of a J-bolt, which is clearly shown in FIGURES 7 and 8. This J-bolt comprises a J-shaped member 25 having the long leg threaded to receive a wing nut 27. The long side of this item is threaded "permanently" through holes in one part of the disconnectable connection, while the small end is inserted in a hole in the cooperating member of the connecting means and locked into place by the tightening of the wing nut.

In the connections between the upper ends of the cross bars 17 and the upper ends of the vertical frame members 11, 15, as shown in FIGURE 8 the long leg of the J-bolt 25 passes through an opening in the end frame member 11 (or 15). The bracket 23 attached to the end frame member has an opening parallel to the end frame member opening which receives the short leg of the J-bolt. The upper of the cross bar 17 has a hole which registers with the hole in the bracket 23. The cross bar is connected to the vertical end frame member by passing the short leg of the J-bolt through the hole in crossbar 17 before tightening the wing nut 27 to lock it in the hole in bracket 23.

In the connections between the front end frame and its pedestal, as shown in FIGURE 7, the long leg of the J-bolt 25 passes through both the end frame member 11 and the "pin" insert 29 to retain the pin insert with one of the elements of the connection when the disconnectable connection is broken. Each of the ends of the vertical end frame members 15, 11 is adapted to form similar pin and J-bolt connections. Consequently, the scaffold frame sections can be stacked one on top of another to form a scaffold more than one unit in height.

To facilitate adding a second unit to a first scaffold unit, hinge elements 31 and 33 are attached to the upper ends of the end frame members 15 of the back end frame. Hinge elements 33 complements hinge element 31 whereby two exactly similar scaffold units can be joined back to back by the hinge elements. One unit can then be swung upside-down on top of another unit as shown in FIGURE 14, the second scaffold frame section may be with or without its carriage, however, to add more sections to the first two, it is necessary to remove the carriage from each section except the base section.

The platform C of the scaffold comprises a rectangular sheet 35 with bracket-like elements 37 fastened to its underside adjacent the ends, these bracket-like elements engage the transverse members 13 of the end frames to retain the platform at the desired level. The platform E may also have hand holes 39 through the rectangular sheet 31 for convenient handling of the platform.

Of course, it is not necessary to use the platform E with the scaffold of the invention as heavy wood boards or planks are suitable for use also. However, when appropriate brackets are used on the platform to engage the transverse frame members of the end frames and rigidly hold them, the platform of the invention is particularly desirable since for low level scaffolds the cross braces can be done away with on one side of the structure.

The scaffold structure is collapsed and folded in the

following manner as shown in the sequence of FIGURES 1, 12 and 13 of the drawings.

- (a) The platform is removed from the scaffold.
- (b) The J-bolts are loosened at each of the disconnectable connections.

(c) The front end frame is lifted free of its pedestal member and the front end frame is brought together together against the back end frame, the X-brace closing scissors-like.

- 10 (d) The collapsed structure is then rotated about the header 9 of the back end pedestal to a horizontal position supported by the cross member 41 on the carriage.

The scaffold is preferably made of light material such as aluminum to increase the ease of handling. The particular embodiment shown is made largely of tubular stock having a square cross section, however, stock having round cross section can also be used in the invention. The applicants, however, found that the scaffold can be more conveniently made with the square cross section material. One element in this particular embodiment of the invention, the header element of the rear pedestal is of necessity made of tubular stock of round cross section to form a pivoting connection between the pedestal and the end frame. The X-brace members are 15 conveniently made of bar stock having a U-cross section providing the greatest rigidity for the least weight. The long X-brace members are sufficiently flexible so that in the horizontal folded position they can be made to avoid the front pedestal members.

20 30 I claim:

1. A folding scaffold unit comprising in combination, a horizontal base frame including a pair of parallel side frame members, a first end frame member extending between one end of said side frame members and a second 35 end frame member extending between said side frame members spaced from the other end thereof, a first pedestal extending upward from the base frame along the first end frame member, and a second pedestal extending upward from said base frame along the second end frame member, the first pedestal comprising two uprights each located at the junction of the side frame members with the first end frame member, the second pedestal comprising two uprights each located at the junction of the side frame members with the second end frame member and a cross 40 frame member extending between the respective uprights of said second pedestal, spaced apart vertical frame members pivotally engaging said cross frame member and extending upwardly therefrom, a cross brace member of a first pair pivoted to the lower end of each of said first pair of vertical frame members, a cross brace member of a second pair each extending transversely to one of said 45 first pair and pivoted thereto at an intermediate point, each of said second pair of cross braces being disconnectably connected to one of said first vertical frame members adjacent the top and pivotally connected to one of a second pair of vertical frame members adjacent the bottom, the bottom end of each of the second vertical frame members being disconnectably connected to said 50 second pedestal, each of the first pair of cross brace members being disconnectably connected to one of said second pair of vertical frame members adjacent the top thereof.

- 55 60 65 70 75 2. A scaffold unit as claimed in claim 1 in combination with a relocatable platform comprising a platform surface having at its ends brackets for engaging the transverse members of the vertical end frames.

3. A scaffold unit as claimed in claim 1, in which the vertical upright frame members of the end frame pivotally connected to the first pedestal has at its upper end hinge elements capable of connecting with cooperating hinge elements on a like scaffold unit whereby one scaffold unit may be swung upside-down on top of another scaffold unit.
